United States Patent Office

Des. 197,455
Patented Feb. 4, 1964

197,455

SINK FITTING OR SIMILAR ARTICLE

Frederick Gordon Mackay and Gerald W. Schmidt, Tarzana, Calif., assignors to Price-Pfister Brass Mfg. Co., Los Angeles, Calif., a corporation of California

Filed Apr. 8, 1963, Ser. No. 74,347

Term of patent 14 years

(Cl. D91—3)

FIGURE 1 is a side elevational view of a sink fitting or similar article embodying our new design;

FIG. 2 is an elevational view taken in the direction indicated by the arrow 2 of FIG. 1; and

FIGS. 3 and 4 are front and rear elevational views thereof.

The dominant features of our design reside in those portions shown in full lines.

We claim:

The ornamental design for a sink fitting or similar article, substantially as shown and described.
